UNITED STATES PATENT OFFICE.

JOHN PARKINSON, OF PHILADELPHIA, PENNSYLVANIA, ASSIGNOR OF ONE-HALF TO JOHN PARKINSON, JR., AND GOTTLIEB SCHMIDT, OF SAME PLACE.

MANUFACTURE OF CAR OR OTHER WHEELS.

SPECIFICATION forming part of Letters Patent No. 508,180, dated November 7, 1893.

Application filed June 9, 1892. Serial No. 436,061. (No model.)

To all whom it may concern:

Be it known that I, JOHN PARKINSON, a citizen of the United States, residing in the city and county of Philadelphia, State of Pennsylvania, have invented a new and useful Improvement in Apparatus for the Manufacture of Car or other Wheels, which improvement is fully set forth in the following specification and accompanying drawings.

10 My invention consists of an apparatus for forging car or other wheels, the same embodying dies, beds and heads of novel construction, and means for setting, gaging and guiding the work as it progresses, as will be hereinafter set forth.

Figure 1 represents a front view of a portion of an apparatus for forging car wheels embodying my invention. Fig. 2 represents a partial side elevation and partial vertical section thereof on line x, x , Fig. 1. Fig. 3 represents a vertical section of another portion of the apparatus. Fig. 4 represents a plan view of the lower die shown in Fig. 3. Fig. 5 represents a section of a portion of the lower die Fig. 3, on an enlarged scale. Fig. 6 represents a vertical section of a portion of the apparatus employed for the first step of forging a car wheel embodying my invention. Fig. 7 represents a vertical section of the die 30 and portion of the head shown in Fig. 1. Figs. 8 and 9 represent front views of portions shown in Fig. 6. Fig. 10 represents a view similar to that shown in Fig. 6, excepting that the head thereof is lower, and the blank in different position and condition. Fig. 11 represents a detached view of the gage and guide shown in Figs. 6, 9 and 10. Fig. 12 represents a view of the blank and the successive forms imparted to the same, including the shaped wheel.

Similar letters of reference indicate corresponding parts in the several figures.

Referring to the drawings:—A, Figs. 1, 2 and 3 designates a hammer which is properly guided on the frame B, and receives power in any suitable manner.

C, Figs. 6, 9 and 10, designates a bed having mounted on the side above the flat face D thereof, the guide roller E, carried in bearings on the gages H.

F designates a head which is located above the bed C, and having a flat working face G. On the sides of the face D, are gages H for the purposes to be hereinafter explained.

J, Figs. 1 and 2 designates a head which is provided with a flange-forming recess K in the center of its face L, and below the same is the anvil-die M, which has a vertical recess N in the base of which is a flange-forming recess P. Journaled in brackets secured to the walls of the recess N, at or near the upper end thereof is a roller Q, and at the front of the recess P, is a leg R, and a table S. The die M is adjustably held in a suitable bed T at the bottom of the frame B, and may be removed therefrom when desired.

U, Figs. 3, 4 and 5 designates a finishing die which has a recess W on its working face, the same being of the shape of a portion of one side of a car wheel and above the same is a plunger or head X, having a working face Y which is of the shape of the portion or half of a car wheel. On the sides of the top of the die U are guide and holding pins Z, which may be placed against the periphery of the partially-formed wheel, as shown in Fig. 5, said pins being fitted in blocks A', and held thereon by screws or bolts B', said blocks being vertically movable in openings C' in the die, by which provision the pins may be applied in adjusted position and afterward raised, turned and moved as desired. Within the die U, is a plunger D' which may be employed for removing the finished wheel if so desired.

The operation is as follows: A blank or cylindrical piece of metal, such as is shown at E', Fig. 12, is placed on the face D of the bed C, Fig. 6, and the head F operated so as to squeeze or work said blank and impart to it an approximately-perfect circular periphery. During this operation the blank is turned by a suitable bar F', shown in dotted lines Fig. 6, said blank revolving upon the roller E. The blank or piece as worked, is now removed and placed endwise on said face D, and hammered by the head F, so as to be flattened out to an extent limited by the gages H, H, as shown in Figs. 8 and 10, after which it is removed and placed in the die M, 100

Fig. 1, in upright position, when the head J is operated, and owing to the recesses K and P, in the faces of said die and head, the shaped piece is properly formed with a flange 5 on its side, as shown in Fig. 1, the descent of the head J being limited by stop pieces J' on the top of the die M. During the operation of flange-forming, a bar G', see Fig. 2, is rested on the leg R as a fulcrum, and worked against 10 the shaped piece so as to rotate the latter, it readily turning on the roller Q, and being thus moved true and steady. When the piece is placed in the die M, it is properly located by means of a pin H', which is passed through 15 the side of the die and pressed against the side of the piece of metal. The flanged metal is removed from the die M, and prevented from dropping on the floor, owing to the table S, and then placed sidewise on the die U and 20 held thereon by the pins Z, when the head X is operated, and thus the final shape is imparted to the metal, converting the same into a wheel. The descent of the head X is limited by stop pieces W', rising from the face 25 of the die U. The opening for the axle may be formed in any suitable manner. The roller Q is mounted on brackets Q', which latter are connected with the die M at the rear of the recess N thereof, as has been 30 stated, and they are provided as shown in Fig. 2, with two or more openings Q², to receive the journals of the roller Q, and thus provide for the adjustability of the latter, relatively to the varying diameters of blanks 35 placed on said die.

It will be seen that the work is expedi-

tiously accomplished and superior results are attained. It will also be seen that the several operations are centrally performed on the several parts of the apparatus, and thus 40 the work will be true and uniform, without liability to be struck out of center, or to strain the adjacent portions of the apparatus.

Having thus described my invention, what I claim as new, and desire to secure by Letters 45 Patent, is—

1. A device for manufacturing car wheels, consisting of a frame, a hammer movable in said frame, a bed with a roller mounted above the flat face thereof, a head with a flat working face, a die M with recesses N and P, jointly with the finishing die U, said parts being combined substantially as described.
2. In an apparatus for forging car wheels, the die M having the recesses N and P, and 55 provided with a holding pin passing through its side, substantially as described.
3. In an apparatus for forging car wheels, the die M, having recesses to receive the body of the shaped piece, and form a flange thereon, and a setting piece H' passed through the side of said die, substantially as described.
4. An apparatus for forging car wheels having a die with a flange shaped recess, a roller journaled above the flat top of a bed, and a 60 leg at the front of said recess, said parts being combined substantially as described.

JOHN PARKINSON.
